UNITED STATES PATENT OFFICE.

GEORGE JOINER, OF NEW YORK, N. Y.

LIQUID-FUEL BURNER.

1,291,012.

Specification of Letters Patent.

Patented Jan. 14, 1919.

Application filed September 8, 1917. Serial No. 190,386.

To all whom it may concern:

Be it known that I, GEORGE JOINER, citizen of the United States of America, residing at New York city, New York, have invented certain new and useful Improvements in Liquid-Fuel Burners, of which the following is a specification.

The present invention relates to a liquid fuel burner, and its object is to provide a 10 simply constructed device by means of which an intensely hot flame may be produced.

In carrying my invention into practice, I provide suitable means for producing a jet or spray of a mixture of such substances as 15 steam and oil, whereby to create a suction action to draw desired quantities of air into the space or chamber where combustion occurs.

The invention is susceptible of embodiment in a great variety of mechanical forms, and for the purpose of illustrating the practical application of the principle involved, I have shown one form of the invention in the accompanying drawing wherein—

25 Figure 1 is a vertical sectional view of a burner adapted to carry out the principle of the invention;

Fig. 2 is a vertical cross sectional view on the line 2—2 of Fig. 1 looking in the direction of the arrows; and

30 Fig. 3 is a vertical sectional view of one of the injectors or sprayers.

It will be understood that the burner may be placed in the fire box of a furnace or in 35 the combustion chamber under a boiler, or in any desired place wherein firing is to be effected.

Referring to the drawing, but more particularly to Fig. 1 thereof, 10 denotes a cylinder which is open at both ends, the inner 40 end 10^a opening into the combustion chamber and the outer end 10^b opening to atmosphere. Arranged within this cylinder, I provide one or more injector units or sprayers, the construction of which is shown in detail in Fig. 3.

The outlet ends of the sprayer units or nozzles are spaced inwardly from the edge or rim 10^a of the cylinder 10 a sufficient distance so that when the mixture issues from the outlet end of the nozzles at a proper velocity, a vacuum will be created within the cylinder 10, thus drawing quantities of atmospheric air into and through the cylinder 10.

Spaced from the cylinder 10, and co-axial therewith, is a second cylinder 11, which has an open end 12 alined with the open end 10^a of the cylinder, the opposite end of the cylinder 11 being provided with a head 12 60 whereby this end of the cylinder is closed. The cylinders 10 and 11 are secured together and held in proper spaced relation by a series of stay bars 13, riveted at 14 to the cylinders 10 and 11 respectively. 65

Referring now to Fig. 3 of the drawing, a description of the sprayer units will be given. Each sprayer unit comprises a chest or box 14^a, one end of which is formed as a constricted outlet nozzle 15 provided with 70 an outlet bore 16. Extending into the chest 14^a and preferably co-axial therewith is a pipe 17, the passage through which may be controlled by a valve or cock 18. This pipe 17 communicates with any gas or fluid under 75 pressure, and in practice I have found it desirable to connect the pipe 17 with a source of steam under pressure. The end of the pipe 17 within the box 14^a is formed as a constricted nozzle 19 alined and concentric with the nozzle 15 of the box 14^a. 80

Opening into the box 14^a is a second pipe 20, the passage through which is also controllable by means of a valve or cock 21. The pipe 20 at its end opposite that opening 85 into the box 14^a is connected with any suitable source of fuel, such as heavy or light oil, or any other fatty substance capable of being burned. In practice, the pipe 20 is connected with a supply of gasoline or other 90 liquid oil.

In Fig. 1, the pipes 17 and 20 are shown as being angular, and as being passed through perforations in the wall of cylinder 10, while in Fig. 3 the pipes 17 and 20 are 95 shown as being substantially straight (except for a bend in pipe 20) and in the form of Fig. 3 these pipes 17 and 20 would extend in a direction parallel to the cylinder 10 throughout their extent. 100

I may use one, two or more sprayer units, dependent upon the character of the installation in which the burner is to be used. For example, a single sprayer unit will be sufficient as a burner under a boiler of say 30 105 H. P., while for a 75 H. P. boiler it would be desirable to have two or possibly three such sprayer units because of the greater amount of heat needed.

In operation a device such as that illus- 110

trated and described would operate to carry out the principle of my invention as follows:—The cocks 18 and 21 would be opened whereby a commingled jet of steam and oil would issue through the bore 16 of nozzle 15. At this point, I desire to make it clear that but an infinitesimal quantity of oil is admitted; there being barely sufficient oil needed for the operation of the burner. The air rushing through the cylinder 10 passes into the cylinder 11, strikes the head 12 thereof, rebounds, and then issues through the opening X between the cylinders 10 and 11. This mixture of fuel and air is ignited by any suitable means. I may ignite the same by placing a quantity of burning oil-soaked waste at the inner end of the cylinder 10, or I may insert a lighted plumber's torch or any other flame into the opening X. When ignition has thus been effected, it will continue just as long as the vacuum in said cylinder is maintained by the continuance of steam flowing through the pipe 17 and issuing at the nozzle 15. I may, of course, regulate the quantity of steam passing through the pipe 17 by means of the valve 18, and I may regulate the pressure of the steam by any suitable means at the steam source.

Copies of this patent may be obtained for five cents each, by addressing the "Commissioner of Patents, Washington, D. C."

What I claim as new and desire to secure 30 by Letters Patent is:—

1. A burner of the character described, comprising a straight chamber open at both ends, a second straight chamber coaxial with and spaced from and entirely clear of the first mentioned chamber and closed at one end thereof, and means for inducing an air current at high velocity to flow through said first mentioned chamber into said second mentioned chamber and out through the 40 space between said chambers.

2. A burner of the character described, comprising a pair of straight coaxial cylinders spaced entirely clear of each other, one of said cylinders being open at both ends 45 and the other thereof being open at one end only, and a sprayer nozzle in the first mentioned cylinder and adapted to induce the flow of an air current through the first mentioned cylinder and into the second mentioned cylinder and out through the space 50 between the said cylinders.

In testimony whereof I have affixed my signature in presence of two witnesses.

GEORGE JOINER.
